ARTICLE DISPENSING RECEPTACLE

Andrew Chappory, Brooklyn, N. Y., assignor to National Biscuit Company, New York, N. Y., a corporation of New Jersey

Application August 31, 1955, Serial No. 37,737

Term of patent 14 years

(Cl. D52—2)

Fig. 1 is a side elevational view of an article dispensing receptacle, showing my new design; and

Fig. 2 is a view in elevation of the lower portion of the receptacle, as seen from the left-hand side of Fig. 1.

The broken line portions of the disclosure are for illustrative purposes only.

I claim:

The ornamental design for an article dispensing receptacle, as shown and described.
